UNITED STATES PATENT OFFICE.

JAMES N. BUTTERLY, OF FLUSHING, NEW YORK.

SUSPENSORY.

Application filed January 29, 1927. Serial No. 164,479.

The invention relates to a simplified suspensor hung from trousers waist band by means of suspender buttons, thereby dispensing with the use of all metal, buckles, belts and straps.

Figure 1 shows suspensor detached from trousers,

Figures 2 and 3 show the suspensor applied to trousers and

Figure 4 shows a modification of the suspensor.

The suspensor consists of a rectangular sheet of fabric (10). To the corners of the fabric are attached loops of elastic cord 5, 6, 7 and 8. These loops are adapted to be attached to trousers suspender buttons.

These elastic loops are also adapted to ad-

just the suspensor as the wearer requires by turning the loops around the suspender buttons to accomplish the necessary fitting. 20

In the modified form shown in Fig. 4, the material of the suspensor is reduced by cutting away the sides as indicated at 9 and 9.

Having thus described my invention what I claim as new and desire to secure by Letters Patent is:

A suspensor comprising a substantially rectangular sheet of netted fabric and loops of elastic cord attached at the corners of the sheet, the loops being adapted to be twisted 30 one or more times around the suspender buttons of the trousers.

JAMES N. BUTTERLY.
